UNITED STATES PATENT OFFICE.

JOHN LANZ, OF PITTSBURG, PENNSYLVANIA, ASSIGNOR TO THE CARNEGIE STEEL COMPANY, LIMITED, OF SAME PLACE.

CLAMP FOR POLES OR COLUMNS.

SPECIFICATION forming part of Letters Patent No. 634,693, dated October 10, 1899.

Application filed February 23, 1899. Serial No. 706,458. (No model.)

To all whom it may concern:

Be it known that I, JOHN LANZ, of Pittsburgh, in the county of Allegheny and State of Pennsylvania, have invented a new and useful Improvement in Clamps for Poles or Columns, of which the following is a full, clear, and exact description, reference being had to the accompanying drawings, forming part of this specification, in which—

10 Figure 1 is a partial side elevation of a column provided with my improved clamp, and Fig. 2 is a horizontal cross-section of the same.

15 My invention relates to the securing of span-wires, insulators, or other devices to poles or columns composed of a metal shape or shapes having flanges, and is designed to provide an improved clamp for this purpose which can be cheaply and easily made and may be secured to the pole without perforating the flanges.

20 In the drawings I show a pole or column composed of an I-beam 2, having its web portion provided with a central reverse or V-shaped fold 3 and provided with channels 4, secured to its flanges and each having a central fold 5. This form of pole is shown and claimed in my copending application, Serial 25 No. 690,368, filed September 6, 1898; but it is evident that my improved clamp may be used 30 with any metal pole or column having flanges.

35 The clamp itself consists of two collars or hollow castings 6, having hook-shaped ends 7 and provided with a through-bolt 8, which extends through the holes in the castings and by which the hooks are drawn into engagement with the outwardly-extending flanges of the pole.

40 I show my device as arranged for securing telegraph or telephone wires to the pole, in this case each casting 6 having formed integral therewith a plate 9, having a hole 10 located outside the lines of the clamp proper. The cross-piece or insulator-support is laid upon the flat upper faces of these plates and 45 secured by bolts extending through their holes. If desired, in leading the wire from the pole at an angle to the portion leading to the pole a similar clamp may be applied to the opposite side of the pole, one of the castings having the upper plate, and another

cross-piece may be secured to this opposite clamp and to the cross-piece upon the clamp shown, the opposite clamp being placed at a slightly higher level than the one shown. The second cross-piece will thus extend at 55 right angles to the first, and by securing the wire to an insulator mounted upon one arm and thence to an insulator mounted upon the other its angle may be changed as desired.

50 In securing span-wires the castings may be made without the plates and are then preferably formed with lugs, through which another bolt is passed and to which the span-wire extends. The plates 9 may be formed into extended arms and the insulators secured directly to these arms, doing away with the necessity for separate cross-arms.

55 The advantages of my invention result from the simple construction of the device and its cheapness of manufacture, as well as its being placed upon the pole without the necessity of forming holes in the flanges. The clamp may therefore be easily and quickly adjusted to small fractions of an inch.

60 Many variations may be made in the form and shape of the hooked clamps without departing from my invention, since

I claim—

65 1. A clamp for poles or columns, comprising two hooks arranged to engage the flanges of the pole and having their shanks in line with each other, said hooks being of sufficient width to prevent twisting and a single bolt exterior to the line of the flanges and extending through both hook-shanks, to draw them 70 toward each other; substantially as described.

75 2. A clamp for poles or columns, comprising two hooks arranged to engage the flanges, each hook having a supporting-plate for a cross-piece, and a bolt exterior to the flanges and engaging the shanks of both hooks to draw them toward each other; substantially 80 as described.

85 In testimony whereof I have hereunto set my hand.

JOHN LANZ.
